CONTAINER

Chester M. MacChesney, Chicago, Ill., assignor to
 Acme Steel Company, Chicago, Ill., a corpora-
 tion of Illinois

Application May 24, 1945, Serial No. 595,541

1 Claim. (Cl. 229—47)

1

This invention relates to improvements in containers of a type adapted for use in storing and shipping various powdered and granular materials and, also, to improvements in protective devices which may be used, for example, in reinforcing and protecting rolls of paper or fabric or other packages.

Many forms of containers comprising annular walls of fibreboard or the like and end walls formed largely or wholly of metal have heretofore been known but most of them have had the disadvantage that the end walls could not readily be secured in place without auxiliary fastening means and presented corresponding difficulty when it was desired to remove the contents.

The principal object of the present invention is to provide a container of the type referred to comprising means for securing the end walls in place without the use of any securing means engaging the annular or outer wall of the container. A further object is to provide an improved container in which end walls are secured in place on an annular or outer wall by an interconnection between the end walls. Another object is to provide a container comprising means for moving the end walls into tight engagement with an annular wall by relative rotation of the end walls about the axis of the container which effects the shortening of a connecting member extending between the end walls. Still another object of the invention is to provide a container comprising an annular wall and two end walls attached to each other by spaced connecting members or by a single connecting member of substantial width which connecting member or members are adapted to be shortened in effective length by the twisting thereof effected by relative rotation of the end walls or parts carried thereby, whereby the end walls are drawn together and into engagement with the ends of the annular wall in which positions they are held by frictional engagement with said annular wall. Other objects relate to various features of construction and arrangement which will appear more fully hereinafter.

The nature of the invention will be understood from the following specification taken with the accompanying drawings in which several embodiments are illustrated. In the drawings,

Figure 1 shows an axial vertical section through one form of container embodying the present invention with the upper end wall elevated from the annular wall of the container and with this upper end wall illustrated by dotted lines in a laterally displaced position which permits the filling of the container;

Fig. 2 shows a vertical axial section similar to that of Fig. 1 illustrating the relative positions of the parts after a relative rotation of the two end walls which has twisted and shortened the connecting device extending between the end walls, consisting of a pair of wires, thereby

2

moving the end wall or cover into tight engagement with the annular wall;

Fig. 3 shows a vertical axial section through a roll paper package embodying the features of the present invention, wherein the ends of the roll of paper are protected by metal plates or caps attached together by spaced wires extending through the central aperture of the roll and capable of being twisted to move both cap members into engagement with the ends of the roll, the twisted condition of the connecting member and the position of the upper cap on the top end of the roll being illustrated by dotted lines;

Fig. 4 shows a side elevation of a modified form of the invention in which provision is made for discharging the contents of the container by effecting a partial untwisting of the flat metal band which serves as the connecting member through relative rotation of the two end walls, thereby bringing into registry discharge openings which are formed in the margins of the annular wall and of the top end wall or cover;

Fig. 5 shows a partial vertical axial section through another form of the invention which is similar to that shown in Fig. 1 except that the connecting members extending from the bottom wall are attached to an auxiliary cap adapted to close an opening in the top wall or cover of the container;

Fig. 6 is a partial vertical axial section through a further modified form of the invention in which the end walls comprise metal rims and relatively rotatable central metal disks which engage other disks seated on the flanges of the rims, the metal disks being connected by members adapted to be shortened by twisting;

Fig. 7 shows a vertical section through still another form of the invention in which the end walls of the container are united through the intermediate chamber of the container by two pairs of connecting members, each pair being adapted to be twisted together by the relative rotation of auxiliary cap members to which they are attached;

Fig. 8 shows a partial vertical sectional view through another form of the invention, similar to that shown in Fig. 6, but comprising a special form of cap member which is rotatable within an opening in the end wall of the container; and

Fig. 9 shows a top plan view of the construction illustrated in Fig. 8.

The form of the invention shown in Figs. 1 and 2 of the drawings comprises an annular wall 10, formed preferably of relatively stiff fibreboard or the like, which is adapted to be engaged at its lower end by a bottom wall 11 and at its upper end by a top wall 12, both of which end walls are preferably formed of metal. The bottom wall 11 comprises a disk 11^a united along its annular outer edge with an annular flange 11^b adapted to fit within the lower end of the annular wall 10. The flange 11^b is united with a radially extending part 11^c engaged by the end of the wall 10 and

this part 11^c is united with a cylindrical flange 11^d which extends upwardly on the outside of the lower edge of the wall 10 and terminates in an annular bead 11^e. The top wall 12 similarly comprises a disk 12^a formed integrally with an annular upwardly extending flange 12^b which is adapted to fit within the upper end of the annular wall 10. This flange 12^b is united with a radially extending part 12^c adapted to engage the upper end of the wall 10 and this part 12^c is united with a cylindrical flange 12^d which terminates in an annular bead 12^e.

For the purpose of attaching the end walls together and securing them to the annular wall 10, they are connected together by a connecting device comprising two spaced wires 13 which are formed, preferably of a single wire passing through spaced apertures in the central portions of each of the end walls 11 and 12 and having its ends secured together, as shown at 13^a, so that the wires 13 occupy an axial position within the annular wall 10. The wires 13 are normally of greater length than the annular wall 10 so that after the wall 10 has been moved into engagement with the bottom wall 11, as shown in Fig. 1, the top wall 12 may be positioned substantially above the upper edge of the wall 10 so that it may be tilted laterally, as shown by dotted lines, to permit the filling of the container with its contents of granular or powdered material or the like. When the container has been filled, the top wall 12 is restored to the position shown by full lines in Fig. 1 and this top wall is then rotated about the longitudinal axis of the annular wall 10, thereby twisting the wires 13 and causing their effective length to be decreased, thereby drawing the two end walls together until the top wall finally assumes the position shown in Fig. 2, wherein the part 12^c thereof is seated upon the upper edge of the wall 10 and its flange 12^d extends downwardly around the top portion of the wall 10, while the flange 12^b fits within the annular wall. When this condition has been reached, it will be found that the frictional engagement between the end portions of the annular wall and the flanges of the end walls will be sufficient to hold the end walls against relative reverse rotation so that they will remain in the relative positions shown in Fig. 2 during the storage and shipment of the filled container while, at the same time, the annular flanges of the top and bottom walls support the annular wall in both radial directions. When the user desires to remove the contents of the container, the top wall 12 is rotated about the axis of the container in a direction which is the reverse of that employed during its application to the annular wall, thereby untwisting the wires 13 and permitting the elevation of the top wall or cover 12 to a position above the wall 10, whereupon the top wall may be moved laterally and tilted to permit the contents of the container to be poured out or otherwise removed.

In Fig. 3 of the drawings, there is shown a modification of the invention wherein the principles of the invention are applied to the protection of a roll of paper 15 which is cylindrical in form and is provided with the usual axial aperture 15^a extending therethrough. The end walls of the paper roll are protected by two metal caps 16 each comprising a radial disk portion 16^a and an annular transversely extending flange 16^b which terminates in an annular bead 16^c. The flanges 16^b are adapted to fit over the ends of the roll 15 and the central parts of the end walls 16

are connected by a connecting device comprising spaced metal wires 17 extending through the central hole 15^a of the roll and having their ends secured to the middle points of the disks 16^a. 5 Upon relative rotation of the two caps 16, they are drawn together by the twisting of the connecting spaced wires so that the upper cap member assumes the position shown by dotted lines in Fig. 3. When the two cap members are fitted 10 over the ends of the paper roll, the frictional engagement of the cap members with the ends of the roll and the frictional engagement of the flanges 16^b with the outer edges of the roll hold the cap members against relative rotation during 15 the storage and shipment of the roll. When it is desired to use the paper roll, a reverse relative rotation of the cap members 16 may be effected to untwist the metal wires 17 and thereby withdraw one of the cap members from one end of 20 the roll, whereupon the wires 17 may be cut off to permit the detachment of both cap members.

The form of the invention shown in Fig. 4 is similar to that illustrated in Figs. 1 and 2 except that the end walls are connected by a flat metal band and except that provision is made for pouring the contents of the container without completely removing either end wall from its engagement with the annular wall. In this form, the annular wall 20, formed of stiff fibreboard or the like, is engaged by a bottom wall 21, similar in construction to the wall 11 shown in Figs. 1 and 2, and by a metallic top wall 22 comprising a horizontal disk 22^a united with an annular depending flange 22^b which terminates in an annular bead 22^c. The middle points of the bottom wall 21 and the top wall 22 are connected by an axially located metal band 23 which is of greater length than the annular wall and which is adapted to be twisted by the relative rotation 30 of the parts to which it is attached, as in the forms of the invention previously described, to draw the two end walls together, thereby causing the top wall 22 to fit over the upper end of the wall 20. The annular wall 20 is provided at one 35 point along its upper edge with a semicircular notch 20^a and the depending flange 22^b of the top wall or cover is provided with a similar semicircular notch 22^d so that, when the two notches are in registration with each other, with the top wall 22 partially removed from the annular wall 20, they form a circular hole through 40 which the contents of the container may be poured therefrom. In order to cause this registration of the notches 20^a and 22^d, it is necessary to effect a partial reverse rotation of the top 45 wall or cover 22 from the position shown by full lines in Fig. 4 so that it ultimately assumes a position shown by the dotted lines, in which latter position the notches register with each other. After discharging a portion of the 50 contents of the container, for example, the top wall 22 may again be rotated in a direction adapted to twist the band 23, thereby restoring the cover to the closed position shown by full lines in Fig. 4, 55 wherein the notches 20^a and 22^b do not overlap or register with each other to any extent.

In Fig. 5 of the drawings there is illustrated a further modification of the invention in which an annular or outer wall 25, formed preferably 60 of fibreboard or the like, is engaged by two metallic end walls including a bottom wall similar to those previously described and a top wall 26 which comprises a removable cap or closure 27. The body portion 26^a of the top wall is formed 65 as a radial disk provided at its outer edge with

a cylindrical flange 26^b which fits within the upper edge of the annular wall 25. This flange is united with a radially extending part 26^c and this part 26^c is united with an outer flange 26^d which terminates in an annular bead 26^e. There is thus formed an annular groove which receives the upper end of the wall 25. It will be apparent that the outer wall 25 may have a square or other non-circular cross section and that the end walls may be given corresponding shapes. The disk portion 26^a of the cover is provided with a central circular aperture 26^f adapted to be closed by an overlapping circular cap or closure 27 when the member 27 is in its closed position illustrated by dotted lines. The cap or closure is provided with a central circular depressed portion 27^a adapted to fit within the aperture 26^f and it has, around its outer edge, an annular upwardly extending flange 27^b which terminates in an annular bead 27^c. Before the container shown in Fig. 5 is filled, the cap of closure 27 normally occupies an elevated position such as that shown by full lines in Fig. 5 and it is adapted to be moved downwardly to the position shown by dotted lines through the shortening of a connecting device 28 which may be formed as a flat metal band, as in the form of the invention shown in Fig. 4, but is here illustrated as a pair of spaced wires 28^a which have their upper ends attached to the cap or closure 27, preferably on opposite sides of the middle point thereof, and which have their lower ends similarly attached to the bottom wall, preferably on opposite sides of its middle point. The two wires 28^a thus occupy substantially an axial position within the annular wall 25 and, upon rotation of the cap or closure 27 about the axis of the container, the two wires 28^a are twisted upon each other and are thereby shortened in effective length so that the cap or closure 27 is drawn downwardly to the closed position shown by dotted lines, wherein it covers the opening 26^f in the body portion of the upper end wall. By a reverse rotation of the cap or closure 27, the wires 28^a may be untwisted, thereby increasing their effective length so that the cap member 27 may be moved laterally to permit the contents of the container to be removed. In this form, the twisting of the wires serves not only to move the cap or closure to its closing position but also to cause the cap to hold the top wall 26 in close engagement with the upper edge of the annular wall. Although the aperture 26^f is preferably located centrally in the wall 26 and the connecting device 28 is preferably attached to the middle point of the disk 27, this form of the invention will operate satisfactorily if both the aperture 26^f and the connecting device 28 are offset from the axis of the container.

In Fig. 6 of the drawings, there is shown still another form of the invention comprising an outer wall 30, formed preferably of fibreboard or the like and engaged at its ends by end walls which may be of substantially identical construction, each including a metal rim, a radial disk and a cap member closing an aperture in the disk. The bottom wall comprises a metal rim 31 having an inwardly extending horizontal flange 31^a united with a flange 31^b which fits within the lower end of the outer wall 30 which may be of circular or other cross section. This flange 31^b is united with a radially extending part 31^c, which is engaged by the lower end of the wall 30, and this part 31^c is united with an outer surrounding flange 31^d which fits around the

outer surface of the lower end of the wall 30, terminating in a continuous bead 31^e. There is thus formed a continuous groove which is fitted by the lower end of the wall 30. The radial flange 31^a is engaged on its outer side by the marginal portion of a disk 32 which is shaped to fit within the flange 31^b and formed preferably of fibreboard or other non-metallic material having substantial strength and resistance to bending stresses.

The top wall comprises a metal rim 33 which has an inwardly extending horizontal flange 33^a united with an upwardly extending flange 33^b formed to fit within the upper end of the outer wall 30. The flange 33^b is united with a radially extending part 33^c which is engaged by the end of the wall 30 and this part 33^c is united with a continuous downwardly extending flange 33^d which terminates in a continuous bead 33^e. There is thus formed another continuous groove which receives the upper end of the wall 30. The horizontal flange 33^a is engaged on its upper side by the marginal portion of a circular disk 34 formed preferably of fibreboard or other non-metallic material having substantial strength and resistance to bending stresses.

The two disks 32 and 34 are connected through the interior of the container by a connecting device adapted to be shortened in effective length by the relative rotation of members which close apertures formed in the disks. In this instance, this connecting device is shown as comprising a pair of normally spaced wires 35 which pass through spaced apertures in the metal cap members 36 and 37 of circular form, which seat against the outer surfaces of the disks 32 and 34, respectively, and close the circular apertures 32^a and 34^a formed therein, when the connecting wires 35 are twisted together. The wires may be secured to the metal cap members or they may be formed from a single wire which is looped through apertures in the cap members and which has its ends secured together as shown at 35^a. The metal cap members have central annular offset portions 36^a and 37^a which fit within the apertures 32^a and 34^a, respectively, and the member 37 is preferably provided with upwardly extending lugs 37^b which may be engaged by the fingers or a wrench when effecting relative rotation of the cap members. Having seated the two metal rims 31 and 33 on the ends of the wall 30, the relative rotation of the cap members 36 and 37 will effect the twisting together of the wires 35 so that their effective length is shortened until the disks 32 and 34 are drawn into tight engagement with the flanges 31^a and 33^a of the rims and the cap members 36 and 37 are moved into tight engagement with the disks. The apertures 32^a and 34^a in the disks are preferably centrally located but they may be offset from the centers, since the tightening of the connecting device is effected by the relative rotation of the cap members.

The form of the invention illustrated in Fig. 7 comprises an outer wall 40, formed preferably of fibreboard or the like and engaged at its ends by end walls 41 which may be made of metal rims and special non-metallic disks as in the form shown in Fig. 6 but are illustrated as comprising radial disks 41^a integrally united at their outer edges with cylindrical flanges 41^b which are adapted to fit within the ends of the annular wall 40. Each flange 41^b is united with a radially extending part 41^c and this part is

united with another cylindrical flange 41^d terminating in an annular bead 41^e. There is thus formed on each end wall 41 an annular groove which receives one end of the wall 40. It will be apparent that the wall 40 may be circular in cross section or of suitable shape and that the end walls 41 may be formed to fit over the ends of the wall 40 regardless of the shape of the latter member.

The end walls 41 are provided with circular apertures 41^f each engaged by a cap member 42 similar in construction to those illustrated in Fig. 6. Each cap member is in the form of a circular disk having an annular flange or bead 42^a which fits within one of the circular openings 41^f and each disk may be provided on its outer side with projecting lugs 42^b for engagement by a wrench or the like for effecting rotation of the cap members. Each cap member 42 is provided with a pair of spaced apertures 42^c which are engaged by portions of a connecting member 43 which is preferably in the form of a metal wire having its ends united at 44 on the outside of one of the cap members. The wires of each pair may be twisted together by effecting relative rotation of the cap members 42 connected thereto, thus shortening the effective length of the composite connecting member and drawing the associated cap members 42 together so that the end walls 41 are thereby maintained in engagement with the annular wall 40. By using a plurality of pairs of connecting wires located at different points across the area of the container, it is possible to apply sufficient pressure to maintain the end walls 41 in proper engagement with the wall 40 regardless of the nature of the contents of the container. The contents may be removed in the manner heretofore described after the cap members have been loosened by untwisting the wires but, in this instance, the upper end wall is shown as being provided with a central opening 41^g engaged by the circular depressed portion 45^a of a cover plate 45 which has a flange 45^b resting on the outer surface of the end wall. Lugs 45^c may be formed on the depressed portion of the cover 45 to underlie the disk portion 41^a of the adjacent end wall to hold the cover in its closed position, it being understood that the cover may be snapped into or out of that closed position due to the resiliency of the coacting disk 41^a.

In Figs. 8 and 9 of the drawings, there is illustrated another modification of the invention according to which the annular wall, not shown, is engaged at its ends by end walls 51, each end wall having a central aperture 51^a engaged by a cap member 52 formed of two sheet metal portions one of which is connected with a pair of wires 53 which may be twisted together for the purpose of shortening the effective length of the connecting member extending between the two end walls thereby holding the end walls in position on the outer wall of the container. In this case the cap member 52 has an outer part 54 provided with two semicircular depressions 54^a adapted to be engaged by a wrench or the like for effecting rotation of the cap member. The outer edges of the member 54 are bent downwardly and inwardly as shown at 54^b to embrace the outer flange 55^a of a complementary member 55 which has a cylindrical body portion 55^b engaging the aperture 51^a and formed integrally with the flange 55^a. The body portion is tapered downwardly and inwardly at its lower end as shown at 55^c and this part terminates in an outwardly and upwardly turned annular flange 55^d which is slotted on op-

posite sides as shown at 55^e so that the wire 53 may be passed around the groove between the flange 55^d and the tapered portion 55^c and then extended outwardly and downwardly through the oppositely disposed slots 55^e. In this way, a rigid cap member is provided for convenient engagement by a wrench to effect the twisting of the wires 53. It will be apparent that this cap member may be employed in place of any of those previously described.

In each form of the invention, two end walls or other parts are connected through the interior of the container by a member or members capable of being shortened through the twisting thereof brought about by relative rotation of end walls, cap members or other parts. To facilitate this shortening of the connecting member, this member should have appreciable width or its wires or other component parts should be substantially spaced apart, since it will be apparent that the rapidity with which the shortening takes effect will depend upon the width of the connecting device. When wires are used, an increased spacing of the wires will shorten the helix formed by each twist so that there will be a corresponding increase in the rapidity of the shortening of the connecting device as the twisting occurs. The length of the connecting member and its width may be selected to suit the purpose for which the container is to be used but, regardless of the proportions of the parts, the container embodies a novel and practical device by which the end walls may be readily secured in fixed position with respect to the outer or annular wall and removed therefrom, without the employment of any of the usual fastening members by which end walls are normally fastened to the annular walls of containers.

Although several forms of the invention have been shown and described by way of illustration, it will be understood that it may be constructed in various other embodiments coming within the scope of the appended claim.

I claim:

45 A container comprising a cylindrical wall, circular end walls adapted to seat on the ends of said cylindrical wall, and spaced wires connected to said end walls on opposite sides of the centers of said end walls and of greater normal length than said cylindrical wall, said wires when twisted together to shorten their effective length being arranged to hold said end walls in engagement with the ends of said cylindrical wall.
